CONTROLLED FLOW BEATER

Frank Hayes, Hoosick Falls, N. Y., assignor to
The Noble & Wood Machine Co., Hoosick Falls,
N. Y., a corporation of New York

Application February 26, 1951, Serial No. 212,753

4 Claims. (Cl. 92—22)

1

This invention relates to beaters or Hollanders employed in the preparation of fibrous material for use in the manufacture of paper and paper products, and more particularly to improved beater construction for accomplishing the necessary fiber change more rapidly and more efficiently. This application is a continuation in part of my co-pending application Serial No. 757,823, filed on June 28, 1947.

Specifically, the machine of my invention is used for cutting, brushing, bruising, fraying, fibrillating or otherwise acting upon fibers or mixing in other ingredients until they are in proper condition to make a sheet of paper. However, it will be understood that the material treated by my improved machine may be used in the manufacture of any product for which the fiber is adapted.

It is accepted in the industry that beater treatment of paper stock is preferable over any other type of refining for the production of high quality papers. However, conventional beaters are expensive to operate and their daily output is so low that in many industrial applications quality is sacrificed in favor of production volume and efficiency.

In the past, a number of attempts have been made to improve beater efficiency, but hitherto none has met with any marked success. The principal reason for this failure to achieve improved efficiency in conventional beaters is the requirement for excessive circulation of stock under the beater roll. Conventional beaters employ a cell spacing in the beater roll of about 2-2½ inches; the smallest hitherto known to be commercially feasible being 1.18 inches. With such cell spacing, an excess of stock must be carried by each cell in order to maintain sufficient stock between the beater roll and bed plate bars to avoid destructive treatment of the stock. However, with smaller cells conventional beaters are inoperative.

I have discovered that striking improvements in efficiency may be attained by employing a cell spacing of less than one inch and by feeding stock to the roll under velocity and in quantity sufficient only to cover the bar edges enough to prevent destructive treatment of stock. With such small cells, substantially all of the stock carried by each cell in the beater roll receives beating treatment during each pass under the beater roll, and little or no stock is carried merely for circulation.

It is an object of my invention to provide a beater wherein the beater roll is relieved of the function of circulating, and wherein substantially

2

all of the stock which passes under the beater roll receives beater treatment.

Among the features of my invention is a beater roll having a cell spacing of less than one inch.

5 Another feature of my invention is the provision of apparatus for controlling the flow of stock to the beater roll under velocity and in a small quantity sufficient only to cover the edges of the bars which define the said small cells.

10 Other objects and novel features of the construction and arrangement of parts comprising my improved machine will appear as the description of the invention progresses.

In the accompanying drawings illustrating a 15 preferred embodiment of my invention:

Figure 1 is a longitudinal sectional elevation through a pulp beater in accordance with my invention;

Figure 2 is a top plan view thereof;

20 Figure 3 is a fragmentary sectional elevation showing a portion of a beater roll and associated bed plate bars of a conventional beater;

Figure 4 is a comparative view, similar to Fig. 3, showing a machine made according to my present 25 invention; and

Figure 5 is a sectional end elevation showing a machined roll bar and cell.

Referring to the drawings, 10 designates a tub, 30 preferably rectangular in plan view, and with a longitudinal wall 11 extending upwardly from the bottom thereof. This wall terminates short of the ends of the tub, thus forming in the tub 10 two parallel passages 12 and 13 extending longitudinally of the tub 10 and communicating with each other at their ends.

35 Located in one of the passages is a mixing propeller 14, the function of which is to thoroughly mix and blend the fiber, and/or color, size, clay or other material with water to constitute the pulp or stock to be treated. During the mixing operation, the propeller 14 driven by a suitable motor diagrammatically illustrated at 44 circulates the stock out of one end of the passage 12, around the adjacent end of the partition wall 11, and into one end of the passage 13, and simultaneously draws the stock from the other end of the passage 13, around the other end of the partition wall, and into the passage 12.

40 Located at a point remote from the tub 10 is a base 15 of concrete or other suitable material. The upper surface of the base 15 is concave and centrally located thereon is a bed plate 16, the upper surface of which lies in a circular arc, the center of which is concentric to the center of the beater roll shaft 21 carrying a beater roll 22.

Mounted on the upper curved surface of bed plate 16 and arranged parallel to each other is a plurality of fixed bed plate bars 17. At the input side of the beater roll is a plate 18 forming part of the intake for said roll. At the output side of the beater roll is a plate 19 which extends upwardly to the top edge of the base 15 and then extends downwardly to form the backfall plate 20, the lower edge of which rests on and is supported on the adjacent wall of the tub.

The beater roll shaft 21 is mounted for rotation in suitable bearings above the bed plate and is driven at the desired speed from any suitable power source 40. The beater roll 22 has on its peripheral face a plurality of parallelly arranged roll bars 23, which may be spaced by woods 36, as in Fig. 4, or machined integral with the roll 22, as shown in Fig. 5.

Over the top of the roll 22 is a curved hood 24, the forward edge of which is connected to the top edge of a deflecting plate 25 and the lower edge of which rests on the top of the partition wall 11. The forward edge of the hood 24 and the meeting edge of the plates 19 and 20 form a discharge orifice 26 at the output side of the beater roll.

At the input side of the beater roll the curved hood 24 joins the upper rounded end of a member 27, which with the plate 18, forms an entrance passage 28 for the stock coming to the roll. Another suitable input arrangement is disclosed in my co-pending application Serial No. 34,269, filed on June 21, 1948.

Member 27 and plate 18 extend downwardly and their lower ends are connected by flange 29 to the flanged upper end of a pipe 30 connected to the discharge side of a pump 31. The intake side of said pump connects with a dump opening 33 in the tub. Pump 31 may be driven from any suitable power source, such as diagrammatically illustrated motor 42 at any desired speed to thereby regulate the amount and pressure of the stock delivered to the roll 22 through the intake 28.

The beater roll may be enclosed in any suitable manner. This roll may have a face width of 48 inches, or any other desired width.

The cells 35 in the roll bars may be spaced center-to-center less than one inch of the periphery of the roll, that is, I may use a small roll cell in which the minimum number of bars is approximately $3\frac{1}{2}$ times the diameter of the roll, and the maximum number is approximately $12\frac{1}{2}$ times the diameter of the roll. That is, the cell spacing may be less than 1 inch and greater than about .25 inch. If the spacing is greater than 1 inch, then an excess of stock is required to keep the bar edges sufficiently covered to prevent destructive treatment, and efficiency falls off rapidly. The minimum spacing of .25 inch represents the threshold below which stock simply blocks the cells.

The small size cells have a number of advantages over the larger cells customarily used (see Fig. 3) in that the fibers being treated in the small cell circulate in a shorter path travel and thus come into engagement with the bed plate bars many times more frequently than in the larger cells, and hence the treatment for each revolution of the roll is greater and the amount of fiber carried less in the small cell than in the large cell. This reduces considerably the horsepower hours per ton required to properly beat the stock and therefore provides a more efficient, useful and improved unit. If desired (see Fig. 5) I may

machine the cells in the bars, giving each cell a rounded formation as at 37 to eliminate the square corners 38 of the conventional cell. This circular shape permits the fiber to fill all areas of the cell, as shown in Fig. 5, and improves the circulation of the fibers within the cell.

In operation, the pulp fiber, color, size, alum, clay, water, and/or other materials to form a batch or charge are placed in the tub 10 and power is applied to rotate the mixing propeller 14 and thereby mix or blend the various ingredients together. The beater roll 22 is now started and when the pump 31 is also started, the mixed and blended material in the passage 12 of the tub is drawn through the discharge orifice 33 and delivered to the roll 22 through the entrance passage 28. As the roll 22 rotates the mixture is caught in the roll cells 35 and drawn over the bed plate bars 17 to thereby cut, brush, bruise, fray, fibrilate or otherwise treat the fibers until they are in the proper condition to make a paper sheet.

It will be obvious that my improved beater roll may be sold as a separate unit to be installed in a paper mill in connection with an existing tub, either adjacent to it or if desired remotely located from it.

It will also be obvious that while I have shown a pump for transferring the stock from the tub to the inrunning side of the beater roll, other transfer or conveyor means may be used.

These and various other modifications may be made without departing from the spirit and scope of my invention as defined by the appended claims.

Having thus described my invention, what I claim as new and desire to secure by Letters Patent is:

1. A beater for pulp comprising, in combination; a rotatable beater roll, means for rotating said roll, a bed plate having bars thereon positioned below said roll, bars about the periphery of said roll spaced to define cells having a size greater than .24 inch and less than 1 inch, and means for delivering stock under velocity to said roll, in a quantity sufficient only to cover the bar edges of said roll and said bed plate.

2. A beater for pulp comprising, in combination; a rotatable beater roll, means for rotating said roll, a bed plate having bars thereon positioned below said roll, bars about the periphery of said roll spaced to define cells having a size greater than the .24 inch and less than 1 inch, a declining plate stock approach to said roll positioned adjacent to and terminating in close proximity to said roll and said bed plate, and means for delivering stock under velocity to said roll in a quantity sufficient only to cover the bar edges of said roll and said bed plate.

3. A beater for pulp comprising, in combination; a rotatable beater roll, means for rotating said roll, a bed plate having bars thereon positioned below said roll, bars about the periphery of said roll spaced to define cells having a size greater than the .24 inch and less than 1 inch, a declining plate stock approach to said roll positioned adjacent to and terminating in close proximity to said roll and said bed plate, and means including a pump for delivering stock under velocity to said plate, and hence to said roll, in quantity sufficient only to cover the bar edges of said roll and said bed plate.

4. A beater for pulp comprising a rotatable beater roll, means for rotating the beater roll, a bed plate associated with the beater roll, a tub,

a pump, ducts, the beater roll and bed plate being located apart from the tub and being fed through the ducts by the pump, said beater roll having a plurality of bars thereon defining cells spaced less than 1 inch by 1 inch, and at least .24 inch, said pump being controllable independently of the beater roll to supply pulp to said roll, at any given speed of rotation thereof, in a quantity and sufficient only to cover the bar edges of said roll.

FRANK HAYES.
